UNITED STATES PATENT OFFICE.

DENNIS SHEA, OF PORTSMOUTH, AND ROMANZO TREFETHEN, OF DOVER,
NEW HAMPSHIRE.

FUNNEL-BLOCK FOR PARTITIONS OF BUILDINGS.

SPECIFICATION forming part of Letters Patent No. 257,771, dated May 9, 1882.

Application filed December 23, 1881. (No model.)

To all whom it may concern:

Be it known that we, DENNIS SHEA, of Portsmouth, in the county of Rockingham and State of New Hampshire, and ROMANZO TREFETHEN, of Dover, in the county of Strafford and State aforesaid, citizens of the United States, have invented an Improvement in Funnel-Blocks for Partitions of Buildings, of which the following is a full, clear, and exact description, reference being had to the accompanying drawings, making part of this specification, in which—

Figures 1 and 2 are perspective views of funnel-blocks made in accordance with our invention. Fig. 3 is a vertical section of our improved block applied to the partition of a building. Fig. 4 is a side elevation of the same, illustrating the manner in which it is supported between the studs by the laths. The ordinary rectangular funnel-blocks which are used in the partitions of buildings to prevent the contact with the surrounding wood-work of stove-funnels passing through them have hitherto been made of uniform thickness throughout, with smooth level faces adapted to lie flush with the surfaces of the partitions in which they are placed. Funnel-blocks of this description are supported in place between the studs by means of a frame built especially for the purpose, within which the block is inserted and tightly wedged to prevent it from being pushed through from either side, the thickness of the block being somewhat greater than that of the studs, so that when the laths and plastering are applied the latter can be made to lie flush with the surface of the block or extend over it, as desired. These funnel-blocks are, however, objectionable, for the reason that the necessity of constructing special frames for holding them adds considerably to the cost of building, while, should the surrounding wood-work shrink, the block will become loose, and as there is nothing to hold it in place within its frame or aperture it is then liable to be displaced by jarring or other cause, so as to project on one side or the other beyond the surface of the plastering, thus marring the appearance of the apartment.

Our invention has for its object to overcome these difficulties; and it consists in a funnel-

block having rabbeted edges on each side, forming tongues or projecting portions of less thickness than the body or main portion, the shoulders thus formed enabling the block to rest directly upon the laths, which fit into the rabbets at its edges, thus enabling us to dispense with the ordinary supporting-frame heretofore used, while the tongues extending out between the two series of laths on opposite sides of the partition serve to effectually hold the block in place at all times, as desired.

In the said drawings, A, Fig. 1, represents a funnel-block composed of artificial stone, soapstone, or other suitable material. Around the edges of this block, on both sides, are rabbets or grooves *b*, forming tongues or projecting portions *c*, of less thickness than the body or main portion of the block. When the block is to be set into a partition, B, the laths *d*, Figs. 3 and 4, are first nailed to the studs *e* up to the point where it is desired to insert the block, which is then put in place, with the shoulders *f* resting on the upper edges of the laths, which fit into the rabbets or grooves *b*, and thus support the block without the employment of the frame heretofore necessary, the cost of which is thus saved. The laths are then nailed on against the upper tongue, *c*, and around the sides of the block, as seen in Fig. 4, when the partition is ready for the plaster, the tongues *c* extending out and fitting between the two series of laths *d* upon opposite sides of the partition, as seen in Fig. 3, and thus serving to effectually hold the block in place against any force or jar which may tend to push it out from either side, no wedges or other fastening devices being required, as the block cannot become loose or displaced by reason of any shrinkage of the surrounding wood-work. The thickness of the body or main portion of the block is such that its faces will project out beyond the surfaces of the laths sufficiently far to allow the surface of the plaster to lie flush therewith, as would be the case if a soapstone block were employed, to which plaster would not adhere; but where the block is composed of artificial stone or other substance to which plaster will adhere its face may be coated, if desired, with plaster up to the edges of the funnel-hole *g*, as seen in Fig. 3, in which case the

faces of the funnel-block would be made to project even with the faces of the laths, or only a little beyond them. Where the studs are placed so near together that the block will just fit between them, two of its edges only on each side would require to be rabbeted, as seen in Fig. 2.

Where the funnel-block is composed of artificial stone or cement which can be molded, our improvement adds nothing to the cost of the block, while by its use much time and labor can be saved and a neater and more substantial job secured than is possible with a block of the old construction.

We are aware that heretofore stove-pipe thimbles have been constructed with an interior sheet-metal cylinder having projecting edges and surrounded by a perforated sheet-metal drum, against the periphery of which the laths rest, and which is secured to said laths or to

the studding by means of sheet-metal ears and nails. We make claim to no part of such construction; but,

Having thus described our invention, what we claim as our invention, and desire to secure by Letters Patent, is—

As a new article of manufacture, a funnel-block, A, having its edges rabbeted at b on each side to form tongues or projections c of less thickness than the body of the block, and adapted to fit between the two series of laths on opposite sides of a partition, substantially as and for the purpose set forth.

Witness our hands this 20th day of December, A. D. 1881.

DENNIS SHEA.
ROMANZO TREFETHEN.
In presence of—
JOHN EMERY,
JOHN SHEA.
